Patented July 10, 1962

193,208

PORTABLE WASHBOARD

William J. Graham, 31 College NE., Grand Rapids, Mich.

Filed May 22, 1961, Ser. No. 65,260

Term of patent 14 years

(Cl. D49—1)

FIG. 3 is a cross-sectional view thereof taken on the line 3—3 of FIG. 1 on an enlarged scale.

The rear not shown, is plain.

I claim:

The ornamental design for a portable washboard, as shown.
